UNITED STATES PATENT OFFICE.

OSCAR T. CARLSON, OF LINDSTROM, MINNESOTA.

COMBINATION-TOOL.

1,344,114.

Specification of Letters Patent. Patented June 22, 1920.

Application filed February 21, 1917. Serial No. 150,043.

To all whom it may concern:

Be it known that I, OSCAR T. CARLSON, a citizen of the United States, residing at Lindstrom, in the county of Chisago, in the State of Minnesota, have invented certain new and useful Improvements in Combination-Tools, of which the following is a specification.

This invention relates to improvements in combination tools and more particularly to that class used about the house, workshop or farm. A further object is to produce a tool that, while adapted for a variety of uses, is cheap to manufacture, of few parts and that is of light construction and easy to handle.

With the foregoing and other objects in view the invention consists in the combination and arrangement of parts to be herein-after fully described, pointed out in the appended claim and illustrated in the accompanying drawings which form a part of this specification and in which—

Figure 1 is a view of the tool in side elevation,

Fig. 2 is a front view of the tool,

Fig. 3 is an end view of the tool,

Fig. 4 is a section taken on line 4—4 of Fig. 1,

Fig. 5 is a section taken on line 5—5 of Fig. 1,

Fig. 6 is a section taken on line 6—6 of Fig. 1, and

Fig. 7 is a view of the opposite side of the tool from that shown in Fig. 1.

Like reference characters denote corresponding parts throughout the several views.

The reference numerals 1, 2 denote the handles which at their upper ends form cheeks 3, 4 which, when the handles are closed or brought together, abut each other, and said cheeks are formed with opposed V-shaped transversely extending grooves 5 thus forming wire splicers. The two pieces 45 of wire to be spliced are placed in the grooves and the handles pressed tightly together, or the wire strands may first be manually wrapped about each other and then placed in the grooved cheeks and the 50 handles pressed tightly together. The handles 1, 2 terminate in integral rounded disks or flattened portions 6, 7 respectively which are of substantially half the transverse diameter of their handles thus forming curved

shoulders 8, 9 upon said handles, the shoulder 8 of handle 1 abutting the portion 7 and the shoulder 9 abutting the rounded portion 6. The rounded portions 6, 7 are connected by pivot bolt 10, and each portion 6 or 7 is formed with a peripheral notch 11. The notched portions 11 coöperating with each other form a nail or wire cutter. The nail or wire to be cut is placed in said notches when they register with each other and the handles 1, 2 then opened thus severing the work held in said notches.

The disk 6 is integral with a heel 12 formed with a transverse semicircular groove 13 formed with threads 14, with a relatively smaller semicircular undulating groove 15, and with a transverse channel 16 merely to lighten its construction. The said heel is formed, further, with the hammer-head 17, with one lateral face having a beveled portion 18, and with a rib 19 which is formed with a groove 20. The disk 7 is integral with a corresponding hammer-head section or toe 21 which is formed with the transverse semicircular groove 22, threaded, and with the smaller semicircular groove 23, 80 and with the transverse channel 24 and with one lateral face having a beveled portion 25 to correspond to the beveled portion 18 aforesaid. Said toe is formed further with the rib 26 having the groove 27 corresponding to groove 20 aforesaid. Said toe, further, is formed with the claw 28 that forms a nail-puller.

When the handles are closed the heel and toe sections abut and the semicircular grooves 13, 22 register, as do the similar grooves 15, 23. The portions 13, 22 form a screw-threading device. The body of the bolt to be threaded is placed between said grooved portions and the handles 1, 2 tightly pressed together when the body of the bolt under operation will be threaded. The grooves 15, 23 jointly form a wire-crimper or device for taking the slack out of wire fence. The beveled surfaces 18, 25 jointly 100 form pincers, and the grooved ribs 19, 26 jointly form a staple-puller.

What is claimed is:—

A device of the class described comprising a pair of handles, disks formed thereon and pivotally connected together, a heel formed integrally with one of said disks and provided with a pair of transverse semicircular

grooves, one of said grooves being smaller than the other and undulating and the larger one being threaded, a toe formed integrally with the disk of the other handle and provided with a pair of grooves similar to and adapted to register with the aforesaid grooves.

In testimony that I claim the foregoing

as my own I have hereto affixed my signature in the presence of two subscribing witnesses.

OSCAR T. CARLSON.
